UNITED STATES PATENT OFFICE.

WILLIAM E. SMELZER, OF BUFFALO, NEW YORK, ASSIGNOR TO MONARCH NUSBAUM
PAPER BOX CO., INC., OF BUFFALO, NEW YORK.

BOX FASTENER.

Application filed June 14, 1927. Serial No. 198,818.

This invention relates to a box fastener and a method of making the same.

The box fastener with which card board mailing boxes are equipped is usually struck from a strip of stock metal through a die 5 operation, or a series of die operations, so as to form a bendable tongue for being passed through slots in the box cover and then bent outwardly and downwardly to secure the 10 cover to the box. The body portion of the fastener is usually clinched through or secured to the sides of the box through the intermediary of a plurality of prongs for firmly securing the fastener to the box. It 15 not infrequently happens that the fastener will pull away from the box, when bending the tongue outwardly, and thereby destroy the utility of the box for mailing purposes.

The present invention has for an object to 20 provide an improved fastener and anchorage therefore to insure a longer lived box having greater utility. Another object is to provide flaps or fingers laterally of the tongue for engaging over the upper edge of the box and 25 downwardly against the inner wall thereof to anchor the upper portion of the fastener body to the box against pulling away therefrom. A further object resides in the novel 30 securing of such flaps or fingers in their operative position. A further object of the invention is to shape said flaps so as to snugly 35 embrace the upper edge of the box and effect a neat finish to the fastener where the flaps extend over said upper edge.

The invention also resides in an improved 40 method of forming and attaching these fasteners in an efficient and economical manner.

In the drawings,

Fig. 1 is a perspective view of the body of 45 the box showing two of the improved fasteners applied thereto.

Fig. 2 is a similar view with the cover applied to the box and the pliable tongues of the fasteners bent down to secure the cover 50 in position.

Fig. 3 is a detailed sectional view showing the fastener inoperative or as depicted in Fig. 1.

Fig. 4 is a similar view showing the fas-

tener in its operative position, or as depicted 50 in Fig. 2.

Fig. 5 is a plan view of the stock strip illustrating the steps of die-cutting the fasteners therefrom.

Fig. 6 is an edge view thereof. 55
In proceeding in accordance with the present invention the box herein depicted is of the usual paper box construction employed for mailing purposes, the same comprising a body 1 and a telescoping cover 2, the latter 60 being formed at opposite sides of its top face with slits or slots 3 to receive the bendable or pliable tongues 4 of the fasteners.

Each fastener comprises a body portion 5 having a tongue 4 projecting upwardly from 65 its upper edge and centrally thereof, lateral securing-flaps 6 also projecting from the upper edge of the body portion and at opposite sides of the tongue 4, and a pair of clinching spurs or prongs 7 which are preferably struck out from the body portion of the fastener within the body lines thereof and adjacent its lower edge. 70

In forming the fasteners from the strip of stock 8, the strip is initially provided 75 with a pair of aligned beads or bulges 9 extending inwardly from its opposite edges thereby leaving an intermediate portion from which the tongue 4 is struck and forming concaved seats on the under side to receive the upper edge of the box 1. Following this 80 operation the substantially rectangular flaps 6 are struck downwardly from the marginal edge portions of the forwardly feeding strip so that the flaps will be joined to the fastener body only by the beads 9. Preferably, at the same time the prongs or spurs 7 are 85 punched through to extend from the body substantially at right angles thereto, in a manner similar to the flaps 6. The forming of the flaps partially defines the tongue 4. The next and final step on the forwardly feeding strip is a combined one of completing 90 the formation of the fastener as well as attaching it to a box. The fastener is completed by severing the tongue 4 from the base portion of the succeeding fastener. This is 95 preferably accomplished by striking out the

free end of the tongue from within the base of the succeeding fastener, as indicated at 10, leaving a recess 11 in said base. This not only avoids sharp corners or projections but 5 permits a finished and rounded edge to the tongue void of a raw edge which the user presses against in bending the tongue. In attaching the fastener to the box 1 the flaps 6 are passed over the upper edge of the box 10 with said upper edge engaging in the pre-formed seats 9 and the flaps bent inwardly against the inside of the box. The spurs or prongs 7 are simultaneously forced through the wall of the box and their inwardly pro- 15 truding ends bent clinchingly upward over the downwardly extending free end portions of the flaps 6, thereby firmly and permanently securing the fastener to the box. By leaving the fastener unsevered from the strip up to 20 the final step, the fastener is supported by the strip until it is in a position for attachment to the box. The prongs form flap-securing members which secure the flaps in their operative position and against acci- 25 dental pulling away from the inner surface of the box.

The base or body portion 5 is given a firm and substantial supporting engagement with the exterior surface of the box, such engage- 30 ment continuing below the portion of the box which is penetrated by the prongs 7 by reason of the depending portions 5' which extend on opposite sides of the recess 11. These depending portions 5' extend a considerable 35 distance below the prongs 7 so that any outward pulling on the tongue 4 will be effectively resisted by the broad and deep body portion. By striking the prongs 7 from the body portion at a distance above the lower mar- 40 ginal portions thereof, the flaps 6 may be con- siderably shortened. There is, therefore, provided a box fastener in which a complete embracement of the box is provided for in that the prongs 7 overlap the flaps 6, and regard- 45 less of the length of the flaps 6 and the loca- tion of the prongs 7 the body portion 5 will be accorded a firm and substantial support against the box by reason of the lower de- pending marginal portions 5'.

50 As a further means of effecting a neat finish to the tongue as well as to reinforce the same, a bulge or knob 12 is pressed therefrom. This knob is preferably formed during the first step, when the seats 9 are formed, the 55 same being pressed downwardly so as to be on the exterior of the bent-over tongue. The free end of the tongue is reinforced against bending and insures the line of fold or bend locating itself adjacent the base of the tongue.

60 The beaded portion 9 provides a pre- formed pocket or seat to receive the upper edge of the box when the flap is bent over against the inside of the box, thereby accord- 65 ing definite lines of fold to the flap and facilitat- ing the bending of the flap over said upper

edge to effect a neat finish. With the flaps engaging over the upper edge of the box the upper portion of the fastener body is securely held against pulling or tearing away from the box at this point when the tongue is bent 70 outwardly to a cover-securing position. The flaps further provide a solid surface onto which the inwardly protruding ends of the prongs 7 may be clinched, thereby avoiding tearing the fiber of the box by embedding the prongs thereinto, which latter method has always resulted in weakening the wall structure at such point or points receiving the em- bedded prongs. 75

I claim:

1. A box fastener comprising a body por- 80 tion having a cover-securing tongue, spaced flaps arranged on opposite sides of the tongue for engaging over the upper edge of a box, and prongs struck from the lower part of the body portion within the body lines thereof for piercing the box and clinchingly engaging over the flaps within the box. 85

2. A box fastener comprising a body por- 90 tion having spaced independent flaps on its upper edge for bending over the upper edge of a box, a cover-securing tongue projecting from the upper edge of the body portion be- 95 yond and between the flaps, and spaced prongs struck from the lower part of and within the body portion for penetrating the wall of a box and being bent backwardly over the downwardly bent flaps.

3. A box fastener comprising a body por- 100 tion having a cover-securing tongue project- ing centrally from its upper edge, spaced in- dependent flaps on said upper edge for bend- 105 ing over the upper edge of a box, said tongue being arranged between said flaps, spaced prongs struck from within the body portion beneath respective flaps for penetrating the box, and spaced bearing portions depending from the lower edge of said body portion beneath respective prongs, each bearing por- 110 tion being in substantial alignment with a respective prong and flap. 110

4. A box fastener comprising a body por- 115 tion having a cover-securing tongue project- ing centrally from one edge, a flap on each side of the tongue projecting from said edge for being bent downwardly over a portion of the box, depending bearing portions on the opposite edge of the body portion in sub- 120 stantial alignment with said flaps for flatly engaging the box surface, and spaced prongs each struck from between an aligned flap and bearing portion for penetrating the box and being clinchingly engaged over the respective flaps to secure the latter against acci- 125 dental disengagement. 125

5. A box fastener comprising a body hav- 130 ing a cover-securing tongue projecting cen- trally from its upper edge, a flap on each side of the tongue and independent thereof and of the companion flap and projecting from

said upper edge for being bent inwardly and downwardly over the upper edge of the box, and spaced prongs each underlying a respective flap and arranged inwardly from the side 5 and lower marginal portions of the body, said prongs being struck out from the body portion for penetrating the wall of the box and being bent upwardly over the down-turned free end portions of said flaps thereby forming therewith an anchorage on each side of the tongue completely encircling a portion of the 10 box.

WILLIAM E. SMELZER.
